(57) CLAIM

The ornamental design for a jewelry display, as shown and described.

DESCRIPTION

FIG. 1 is a front view of the jewelry display showing my new design;

FIG. 2 is a left side view thereof;

FIG. 3 is a right side view thereof;

FIG. 4 is a rear view thereof; and,

FIG. 5 is a top view thereof.

The bottom of all embodiments is unornamented and forms no part of the claimed design.

1 Claim, 3 Drawing Sheets

FIG. 1

FIG. 5
